DESIGN FOR A CIRCULATING HEATER

Boyd W. Tullis, Wichita, Kans., assignor to The
Coleman Lamp and Stove Company, Wichita,
Kans.

Application May 21, 1937, Serial No. 69,471

Term of patent 7 years

To all whom it may concern:

Be it known that I, Boyd W. Tullis, a citizen
of the United States of America, residing at Wichita,
in the county of Sedgwick and State of Kansas,
have invented a new, original, and ornamental
Design for Circulating Heaters, of which
the following is the specification, reference being
had to the accompanying drawing, forming a
part thereof.

Fig. 1 is a top plan view of a circulating heater
showing my new design;

Fig. 2 is a front perspective view thereof; and
Fig. 3 is a rear perspective view thereof.

I claim:

The ornamental design for a circulating heater,
as shown.

BOYD W. TULLIS.
